UNITED STATES PATENT OFFICE

95,756

DESIGN FOR A TEAPOT

Charles Kaiser, Great Neck, N. Y., assignor to Morimura Bros. Inc., New York, N. Y., a corporation of Japan

Application September 1, 1934, Serial No. 53,155

Term of patent 7 years

To all whom it may concern:

Be it known that I, Charles Kaiser, a citizen of the United States and a resident of Great Neck, county of Nassau, and State of New York, have invented a new, original, and ornamental Design for a Teapot, of which the following is a specification, reference being had to the accompanying drawing, forming part hereof.

In the drawing, Figure 1 is an elevation, and Figure 2 is a plan view of a Teapot, showing my new design.

I claim:

The ornamental design for a teapot, as shown.

CHARLES KAISER.
